(57) **CLAIM**

The ornamental design for a dimmer module, as shown and described.

DESCRIPTION

FIG. 1 is a top plan view of a dimmer module showing our new design;

FIG. 2 is a front elevation view thereof, the rear elevation view being the mirror image thereof;

FIG. 3 is a right side elevation view thereof, the left side elevation view being the mirror image thereof;

FIG. 4 is a bottom plan view thereof;

FIG. 5 is a top perspective view thereof;

FIG. 6 is a bottom perspective view thereof;

FIG. 7 is a top plan view thereof, shown as the dimmer module appears in a typical pipe clamp mounted installation; FIG. 8 is a front elevation view thereof, shown as the dimmer module appears in a typical C-clamp mounted installation;

FIG. 9 is a rear elevation view thereof, shown as the dimmer module appears in a typical yoke mounted installation; and, FIG. 10 is a right side elevation view thereof, shown as the dimmer module appears in a typical wall mounted installation.

The dashed lines shown in FIGS. 7, 8, 9 and 10 represent environmental subject matter and form no part of the claimed design.
